UNITED STATES PATENT OFFICE.

DANIEL B. STAUFF, OF UNIONTOWN, PENNSYLVANIA.

GANG-DRILL FOR CUTTING COAL.

1,270,231.

Specification of Letters Patent. Patented June 18, 1918.

Application filed November 9, 1916. Serial No. 130,313.

To all whom it may concern:

Be it known that I, DANIEL B. STAUFF, a citizen of the United States, and a resident of Uniontown, in the county of Fayette and State of Pennsylvania, have invented a new and Improved Gang-Drill for Cutting Coal, of which the following is a full, clear, and exact description.

This invention relates to coal mining machinery and has particular reference to drilling devices for boring a plurality of holes simultaneously in definite spaced relation for the purpose of weakening the natural structure for subsequent reduction by blasting or other suitable means, or for the purpose of making a substantially clean cut by repeated drilling operations or removal of the minimum amount of material where the cut is being made.

The common practice in leading coal mines in western Pennsylvania where the coal seam is comparatively soft and from seven to nine feet in thickness is to drive entries approximately nine or ten feet in width and six or eight feet high in different directions toward property lines, and from these main entries in a similar manner there are excavated or driven lateral entries and rooms sufficient in number to furnish ventilation, haulage roads, and working places for a sufficient number of workmen to mine or load the quantity of coal desired, the work being laborious and sometimes difficult or dangerous. The amount of labor and danger in these operations is reduced according to the thoroughness of the preliminary work of undercutting, overcutting, or shearing, such preparations being necessary in order to provide at least one free or open end or side to the face of the coal before proceeding with its excavation, considerable pick or hand work being required ordinarily to prepare the working face for the next undercut, overcut, or shear.

Among the objects of this invention therefore is to provide a machine to reduce or largely eliminate this pick or hand work by drilling overhead, across the working face, a row of holes near the roof and approximately three inches apart and as deep as the undercut is to be made, so that the force of the blast, if a blast is used, is rendered most effective and least dangerous to the operators and whereby, furthermore, the greatest effi-

cency or buckling effect of the coal is accomplished, laying it down on the floor of the working place, ready to be loaded and delivered from the mine.

Another object of the invention is to provide a portable device adapted to be self-propelled or otherwise along a pair of rails or track, said portable device serving to carry drilling apparatus and the power means for operating the same in a relatively cheap and highly efficient manner.

With the foregoing and other objects in view the invention consists in the arrangement and combination of parts herein described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Fig. 1 is a side elevation of my improved machine, parts being in section on the line 1—1 of Fig. 2;

Fig. 2 is a rear elevation of the same looking in the direction of movement of the machine;

Fig. 3 is a vertical sectional detail on the line 3—3 of Fig. 2;

Fig. 4 is a plan view of the adjustable saddle and parts associated directly therewith;

Fig. 5 is a horizontal sectional detail on the line 5—5 of Fig. 1; and

Fig. 6 is a sectional detail on the line 6—6 of Fig. 4.

Referring now more particularly to the drawings, I show a truck comprising a platform 10 and supporting wheels 11 adapted to be transported by any suitable means carried either upon the platform or elsewhere along a pair of rails 12.

On the front end of the platform is supported in rigid position, as by bolts 13 operating through a flange 14, a vertical telescopic mast, the lower stationary portion of which is indicated at 15 and of a tubular nature. The lower end of this cylinder 15 has a pipe connection 16 with a fluid pump 17 of any well known or suitable nature carried also upon the platform. The upper portion 18 of the vertical support constitutes a piston adapted to reciprocate vertically in the

cylinder 15 under the force of fluid pumped into the bottom of said cylinder. A stuffing box 19 is provided to make a fluid-tight closure for the cylinder and through which 5 the piston 18 slides.

10 The upper end of the piston 18 is threaded for connection with a head plate 20 having a circular flange 20' lying in a plane perpendicular to the axis of the piston. This head plate is screwed tightly upon the upper end 15 of the piston and locked by means of a lock nut 21. The central portion of this member is provided with a central upwardly projecting hub 22 having external screw threads and an internal hemispherical seat 23.

20 indicates a T-head having a downwardly projecting threaded shank 25 extending through the center of an adjusting head 26 which is locked in place by a combined ball and nut 27 and 28. This ball 27 is seated in the hemispherical seat 23 in the hub of the head plate and is secured in such position by means of a cap nut 29 secured upon the threads of the hub 22. By this 25 means the T-head and parts secured thereto are locked to the upper end of the piston 18, but permitted a considerable amount of angular movement with respect to a horizontal plane. A plurality of adjusting screws 30 are tapped through the rim of the adjusting head 26, the lower rounded ends of 30 which bear against the upper surface of the flange 20'. Each of these screws carries a hand wheel 31 for manipulating it. By 35 means of these screws, the head 24 and plate 26 are adjusted into any desired angular position and locked steadily in such position.

40 I provide what I term a carrier frame, the same comprising three parts, first, a pair of arms 32 having their inner ends internally threaded and screwed upon the T-head 24 and extending thence in opposite directions. The outer end of each arm 32 is reduced in diameter and projected through a 45 plate 33 and locked in position by means of a nut 34 tapped upon the extreme end of such arm. A lock nut 35 is tapped into the outer end of each arm and serves to carry an adjustable jack screw 36, to the outer 50 face of which is swiveled a contact head 37. Said plates 33 constitute the second main part of the carrier. Thirdly, the carrier comprises a pair of parallel bars 38 similar to each other and fixed at their opposite 55 ends in the upper portions of said plates 33. These bars 38, lie on opposite sides of the vertical plane of the arms 32 and in a horizontal plane above the horizontal plane of 60 said arms. Jack screws 36 are adapted to be rotated by hand spikes or the like for the purpose of locking the ends of the carrier frame against the adjacent walls of the entry indicated at C, Fig. 2. This operation is predicated upon the hoisting of the carrier frame by means of the hydraulic pump

apparatus, shown at 17, acting through the telescopic standard or support described above.

65 The carrier frame constitutes a suitable and convenient track or support along 70 which a saddle 39 is adjustable. This saddle comprises a body 40 of any suitable rigid construction through which the bars 38 project and which body, furthermore, has 75 slidable engagement at 41 upon the upper portion of the T-head 24 and arms 32 extending therefrom. As will be noted especially in Fig. 2, the arms lie flush with the upper portion of the head 24, whereby there will be no obstruction to the adjustment of 80 the saddle along the carrier frame. The bars 38 are sufficiently rigid to prevent tilting movement of the saddle with respect to the carrier frame. This saddle also includes a substantially vertical wall 42 and a rear- 85 wardly projecting bracket 43 secured to the lower end of the said wall. The top of the saddle is indicated at 44 and supports a pair of parallel bearing blocks 45 extending longitudinally of the carrier frame and spaced 90 parallel from each other. The bracket and wall 42 of the saddle are extended or located rearwardly with respect to the carrier frame sufficiently far to clear the adjusting head 26 and the parts coöperating therewith, 95 see Fig. 1, when the saddle is adjusted from one end of said frame to the other.

100 The body 40 of the saddle is formed with a vertically projecting web 46 which lies in the vertical plane of the axis of the arms 32 and hence midway between the bars 38. Any suitable means may be provided to 105 adjust the saddle lengthwise of the frame or it may be moved by hand to any desired position and then secured by some suitable 110 clutching or gripping means such, for instance, as is indicated in Fig. 5, the same comprising a pair of sleeves 47 embracing the several bars 38, each sleeve having a 115 threaded shank 48, the threads of which are right and left and coöperate with a turn buckle nut 49 extending through a hole 50 in said web 46. Either end of this nut may be grasped by a wrench or the like from beneath the top 44 of the saddle, whereby the sleeves 47 are caused to draw the bars 38 toward each other, causing the same to grip tightly against the edges of the holes in the saddle body through which they extend. By 120 this means the saddle is locked in any desired position.

125 51 indicates a plurality of standard make threaded shafts or feed bars which coöperate with corresponding threads formed in clamp bearings attached to feed bar boxing (well known but not shown in drawings) secured in place by boxing 45. Each 130 of these shafts is adapted to be rotated in said bearings by means of a gear 52 located in the space between said bearing blocks 45

and mounted on a hollow internally lugged shaft (not shown in drawings, but well known to coal drill makers) the lug slidably engaging a shallow slot or groove cut lengthwise in the surface of the feed bar from end to end of same in the fashion adopted by the drill makers and rotating the same; the hollow shaft, feed bar and feeder clamp (not shown) being no part of this invention.

10 Each of these shafts has at its forward end a chuck 53 which carries a coal drill 54 of any suitable type and sufficiently long to make the desired undercut adjacent the ceiling R of the entry. I show four of these 15 shafts and drills operating in a gang in the same plane, but it is to be understood that I do not wish to be limited to this particular number or arrangement of such devices. The several sleeve nuts 52 include gear pinions 53, between each two of which is interposed an idler gear 54 supported or journaled upon short shafts 55 secured to the bearing blocks 45. The central idler 54, however, is provided with an extended shaft 25 55' which carries at its rear end a pinion 56 meshing with a large gear 57 driven from any suitable source of power, such as an electric motor M, shown as supported upon the bracket 43. By this means all of the 30 shafts 51 and drills secured thereto are adapted to be rotated simultaneously in the same direction and at any desired speed.

With the mechanism constructed as above suggested, the operation of the machine 35 may be briefly summarized as follows: With the proper approach being constructed and the truck in position to be propelled either by a self-contained power means carried upon the rear end thereof or otherwise, 40 the drilling apparatus will be projected forwardly adjacent to the place where the next undercut is to be made. By means of the pump 17, the drills will be elevated as may be necessary to bring them into the plane 45 desired and the drills will be fixed in such plane by manipulation of the screws 30 and secured more rigidly by tightening jack screws 36 against walls of working place. The saddle 39 will then be positioned along 50 the carrier frame at any desired place laterally of the entry or line of action and locked in place on the frame. The motor M will then be started, causing the drills to be rotated as desired, making thereby a series 55 of holes as deep as is permitted by the length of the shafts 51. The drills may then be withdrawn and the saddle shifted lengthwise of the frame to make a series of holes in a new place, or if desired another 60 set of holes may be drilled closely adjacent to those first drilled so as to make a practically clear cut by the action of the drill alone. In any event, the cutting action insures that a comparatively slight amount 65 of material will be reduced to a fine form

in making the cut. The operation is easy to control and is of a very rapid nature as compared with the usual mining process.

I claim:

1. The herein described self-contained 70 gang drill comprising a truck, a vertically adjustable telescopic support carried by the truck, a carrier frame secured at the upper end of the support and extending transversely of the line of movement of the truck, 75 a saddle adjustable longitudinally of the frame, and drilling devices and power means therefor carried by the saddle.

2. In a gang drill for coal, the combination 80 of a truck, a vertical and vertically adjustable support secured to the front end of the truck, a head, a universal connection between the head and the vertically adjustable support, a carrier frame secured in fixed position perpendicular to the axis of 85 said head, a saddle movable longitudinally of said frame laterally of the line of movement of the truck, drilling devices carried by the saddle, and means to lock the saddle in position on said frame.

3. In a coal drill, the combination of a 90 truck including wheels for movement of the truck along its track, a vertical support secured to the front end of the truck, means carried by the truck for elevating the support, a head, a universal connection between the head and the upper end of the support serving to provide for the inclination of the axis of the head with respect to the axis of the vertical support, a carrier frame secured 95 rigidly to said head in a plane perpendicular to the axis of the head, means between the head and the support serving to vary the plane of the carrier frame as desired, and drilling devices carried by and longitudinally adjustable of said frame.

4. In a coal drill, the combination of a 100 vertical support, a T-head having its vertical axis in alignment with said support, drilling devices supported upon said head and a universal connecting means between the head and the support, said connecting means including a head plate rigidly secured to the upper end of the support, said head plate having a hemispherical seat and a 105 supporting flange surrounding the same, an adjusting head secured to the first mentioned head and lying mainly in a plane perpendicular to the axis thereof, a ball secured to the two heads and fitted in said seat, and a series of adjusting screws acting between 110 said adjusting head and the flange of the head plate, whereby the axis of the first mentioned head may be varied as desired with respect to the axis of the support.

5. The herein described coal drill comprising an upright support, a head at the upper end of the support having a normally vertical axis, means to adjust the head as desired with respect to the vertical axis of 115 120 125 130

the support, a carrier frame fixed to the head and including a plurality of rigid spaced parallel members, a saddle supported on and movable longitudinally of said members, means to lock the saddle in any position to which it may be adjusted along said members, and drilling means carried by said saddle.

6. The herein described supporting means for coal drills, the same comprising a carrier

frame including a plurality of spaced parallel bars, a guide member parallel to and spaced from said bars, a saddle comprising a body embracing said bars and supported upon said guide member, said body having 15 a web extending between said bars in the plane of said guide member, and gripping means embracing said bars and coöperating with said web to lock the saddle in position.

DANIEL B. STAUF.
